(57) **CLAIM**

The ornamental design for a TRASH CAN LID as shown and described.

DESCRIPTION

FIG. 1 is a top front right perspective view of the TRASH CAN LID of the present invention;

FIG. 2 is a top right perspective view thereof;

FIG. 3 is a right side view thereof;

FIG. 4 is a left side view thereof;

FIG. 5 is a front side view thereof;

FIG. 6 is a rear view thereof; and

FIG. 7 is a bottom perspective view thereof.

The broken lines in the figures show portions of the TRASH CAN LID which form no part of the claimed design.
